UNITED STATES PATENT OFFICE.

MICHAEL E. SOMAN, OF NEW YORK, N. Y., ASSIGNOR TO GREENBERG & SCHWARTZ, A COPARTNERSHIP COMPOSED OF HARRY GREENBERG AND BENJAMIN SCHWARTZ, OF NEW YORK, N. Y.

DESIGN FOR A FINGER RING.

Application filed December 15, 1926. Serial No. 20,057. Term of patent 3½ years.

To all whom it may concern:

Be it known that I, MICHAEL E. SOMAN, a citizen of United States, and a resident of city of New York, borough of Manhattan, county and State of New York, have invented a new, original, and ornamental Design for Finger Ring, of which the following is a specification.

Reference is to be had to the accompanying drawing, in which—

Figure 1 is a side view of a finger ring showing the new design, and

Fig. 2 is an edge view thereof.

What is claimed is—

The ornamental design for a finger ring as shown.

MICHAEL E. SOMAN.
